Primary Examiner — Rosemary K Tarcza(74) Attorney, Agent, or Firm — Michael Best & Friedrich LLP(57) CLAIM

We claim the ornamental design for a helmet cap, as shown and described.

DESCRIPTION

FIG. 1 is a perspective view of a helmet cap.

FIG. 2 is a front view of the helmet cap shown in FIG. 1.

FIG. 3 is a side view of the helmet cap shown in FIG. 1.

FIG. 4 is a back view of the helmet cap shown in FIG. 1.

FIG. 5 is a top view of the helmet cap shown in FIG. 1; and,

FIG. 6 is a bottom view of the helmet cap shown in FIG. 1.

The broken lines shown in the drawings are included for the purpose of illustrating unclaimed portions of the helmet cap and form no part of the claimed design.
